UNITED STATES PATENT OFFICE.

JOHN J. PIERRE, OF FREEPORT, NEW YORK.

COIN-CONTROLLED COLLAR-VENDING MACHINE.

1,191,032.

Specification of Letters Patent.

Patented July 11, 1916.

Application filed February 5, 1916. Serial No. 76,384.

To all whom it may concern:

Be it known that I, JOHN JOSEPH PIERRE, a citizen of the United States, residing at Freeport, Long Island, in the county of 5 Nassau and State of New York, have invented certain new and useful Improvements in Coin-Controlled Collar-Vending Machines; and I do hereby declare the following to be a full, clear, and exact description of the invention, such as will enable others skilled in the art to which it appertains to make and use the same, reference being had to the accompanying drawings, 10 and to the letters and figures of reference 15 marked thereon, which form a part of this specification.

This invention relates to a novel apparatus for vending articles of manufacture, preferably collars, and it has for its object 20 to provide a device of pleasing appearance which may be placed in hotels, railroad stations, Pullman cars, barber shops and other convenient places.

Another object of the invention is to provide 25 a coin-controlled vending machine which may be stocked with collars of various sizes and which will, after the proper coin or coins have been placed therein and the lever manipulated, discharge and present to 30 the purchaser a single collar or article, or a plurality of collars simultaneously.

The invention comprises various details 35 of construction, combinations and arrangements of parts which will be hereinafter fully described, shown in the accompanying drawings and then specifically defined in the appended claims.

The invention is illustrated in the accompanying drawings, in which:

40 Figure 1 is a front elevation of the invention, a part of the outer casing being broken away. Fig. 2 is a side elevation. Fig. 3 is a central vertical section. Fig. 4 is an enlarged detail view of the coin chute and coin 45 operating mechanism. Fig. 5 is a section taken on line 5—5 of Fig. 4. Fig. 6 is a section on line 6—6 of Fig. 5, and Fig. 7 is a detail perspective view of the discharging lever.

50 Reference now being had to the details of the drawings by letter, A represents the housing which may be of sheet metal and comprises front and rear walls, spaced apart by suitable end pieces, and is provided at 55 its top with a hinged lid A' which is provided with a lock A². Between the front

and rear walls, a short distance from the top, is a horizontal partition A³ which forms the bottom of a compartment A⁴ in which collars may be placed on display for the prospective customer to select from, there being one or more styles of the various sizes, the same being plainly visible through the glass plate A⁵, secured in the front wall of the housing. From the horizontal partition A³ down to a proper point the housing is divided into a series of vertical passageways B by vertical strips B' of suitable length, said strips being spaced apart the proper distance to permit of free passage of the packages or collars C as shown. A door D, provided with a lock and hinges, is located at the upper terminus of said vertical chambers B affording means whereby access may be had to the compartments B for the purpose of refilling any or all of the compartments as the occasion may require. The device may have any number of vertical compartments, there being but twelve shown in the present illustration and in such compartment there are shown six packages or collars C, neatly inclosed in a protecting 80 wrapper to prevent soiling.

The front wall of the housing is provided with the proper number of coin receiving 85 slots A⁶ which are in alinement with coin chutes B² formed in the vertical partition B', cover plates B³ forming one wall of the chutes, being secured to the partitions in a suitable manner. Said cover plates B³ extend through the rear wall, as shown in Fig. 4, and are so constructed as to form a continuation of the chute to guide the coin to its operative position. To the rear wall of the housing is secured a second casing D 90 which provides a covering for the coin operating mechanism, which consists of a shaft D' mounted in bearings in each end of said casing D and properly positioned loosely on the shaft D' is a series of discharging levers, 95 designated by letter D². Each lever D² comprises a horizontal sleeve D³ and projecting from the upper surface of which is an arm D⁴, bifurcated at its upper end, and pivoted thereto is a package retaining finger or bar D⁵ which is adapted to be projected 100 through an opening into the corresponding compartment B at a point between the two lowermost collars therein.

Extending downward from the under side 110 of the sleeve D³ is a pair of bifurcated arms D⁶ to which are connected two collar sup-

porting fingers D^7 upon which the lowermost collar C is adapted to rest. Near one end of the sleeve D^3 and projecting at an angle therefrom is a coin-arresting arm D^8 which is positioned directly in the path of travel of the coin.

A manually-operated shaft E is located under the shaft D' and has bearings in the casing D , and one end of said shaft extends outside the casing and has attached thereto a handle E' within easy reach of the customers. The shaft E carries a series of coin-supporting arms E^2 , one for each of the coin chute extensions, the bottoms of which are cut away as at E^3 to receive the upper concaved end of one of the arms E^2 upon which the coin will come to rest after having been deposited in the slot A^6 by the customer.

20 Mounted on the finger D^5 and interposed between the rear wall of the housing and a shoulder D^9 is a coiled spring D^{10} which normally holds said separating finger D^5 in its farthest outward position and at the same time pushes the supporting fingers D^7 inward or until the shoulders D^{11} thereon abut against the rear wall of said housing.

When a purchase is to be made, it is only necessary for the purchaser to select the style by observing the display at the top of the cabinet, and then the size, which is indicated near the slots, as shown in Fig. 1. Having done so, a coin of the proper denomination is placed within the chute and, by a slight raising of the handle, the selected collar will appear in the delivery pan. This is accomplished by the coin rolling by gravity to the end of the chute where it is stopped by the arm D^8 and rests upon the arm E^2 . In this position, the coin acts as a medium for transmitting power from the shaft D' to the discharging lever D^2 which on being rocked in the directions as indicated by arrow (Fig. 4) will thrust the separating arm between the two lower collars in the compartment and at the same time withdraw the supporting fingers D^7 from under the lower collar and permit the same to drop and roll down the incline F to the delivery pan, designated by letter F' . The hand lever E' on being released drops by gravity to its normal position, at rest on the stop F^2 and the coin upon being released from frictional engagement between the two

arms E^2 and D^8 will fall by gravity to the receptacle D^{12} formed in the bottom of the casing D .

It will be seen that the discharging mechanism is duplicated for each compartment, and that a single shaft D' operates the delivery of one or all compartments, thus providing a device which is simple in construction, easy to operate, has no complicated parts to get out of order, and is cheap to manufacture.

What I claim to be new is:

1. In a coin-controlled vending machine, a plurality of vertical compartments, a common outlet therefor, a shaft extending lengthwise of said compartments, a discharge lever for each compartment loosely mounted on said shaft, a separating arm for each compartment carried by said lever, a main operating shaft, a stop arm on the discharge lever, an arm on said main operating shaft for supporting the coin between itself and said stop arm and arranged in the path of said discharge lever, and article supporting fingers movable with said discharge lever and adapted to be withdrawn as a separating finger is thrust between two adjacent packages.

2. In a coin-controlled vending machine, a plurality of vertical compartments, a common outlet therefor, a shaft extending lengthwise of said compartments, a discharge lever for each compartment loosely mounted on said shaft, a separating arm for each compartment carried by said lever, a main operating shaft, a stop arm on the discharge lever, an arm on said main operating shaft for supporting the coin between itself and said stop arm and arranged in the path of said discharge lever, article supporting fingers movable with said discharge lever and adapted to be withdrawn as a separating finger is thrust between two adjacent packages, said supporting fingers having stop shoulders, and springs acting on the separating fingers to hold them in their farthest outward position.

In testimony whereof I hereunto affix my signature in presence of two witnesses.

JOHN J. PIERRE.

Witnesses:

HEY. B. DALLEY,
FRANKLIN H. HOUGH.
